C. E. SACRE

PISTON RING CLOSER

Filed Aug. 22, 1923

Inventor:

Clorence E. Sacre.

By Higdon & Higdon
Attorneys

UNITED STATES PATENT OFFICE.

CLARENCE E. SACRE, OF ST. LOUIS, MISSOURI.

PISTON-RING CLOSER.

Application filed August 22, 1923. Serial No. 658,713.

To all whom it may concern:

Be it known that I, CLARENCE E. SACRE, a citizen of the United States, residing at St. Louis, in the State of Missouri, have 5 invented certain new and useful Improvements in Piston-Ring Closers, of which the following is a specification containing a full, clear, and exact description, reference being had to the accompanying drawing, 10 forming a part hereof.

The invention consists in the novel construction and combination of parts herein-after particularly described and distinctly claimed.

15 The object of my invention is to provide an improved tool for use in closing or compressing split piston-rings in the piston-grooves, so that the piston may be placed in the cylinder (with the compressed rings 20 in place) very quickly, and with the expenditure of very little time or labor; and which tool shall be of simple construction, durable, and of low cost, as well as highly efficient.

25 In the drawings.

Fig. 1 is a top plan-view of my piston-ring closer in its present form, as used in connection with a common piston, and

Fig. 2 is an edge-view of the same.

30 The numeral 1 designates one of a pair of handles, and 2 the other handle of the pair, which are connected by a pivot 3, in a manner similar to that used in pivoting the blades of shears or scissors, so that 35 when said handles are separated or moved in a given direction, say at the handle-ends, the jaws having holes 4 and angular-slots 5, will be correspondingly located.

A circular clamping-band 6 is provided 40 with a perforation 7 near one of its ends, which is slipped into and through its said inclined or angular-slot 5, and is moved therein towards and into the adjacent perforation 7, the construction being such that 45 the said end of said band will be thereby pivotally-connected to one of the slotted and perforated portions of one of said handles, by a sort of hook-construction, which permits the parts to be readily assembled and disconnected.

50 The said pivot 3 should be located comparatively near the slotted ends of said handles 1 and 2, so that sufficient leverage will be provided, for compressing the 55 piston-rings, as well as the said band 6 itself, and in the present case I have located

said pivot at a point about one-fourth the length of said handles.

The said band 6 is preferably made of 60 spring-steel, of sufficient width to cover and compress three adjacent piston-rings if same are of small size, and said band is curved into circular form, having a normal diameter that is considerably in excess of the diameter of the uncompressed or 65 open piston-rings.

A short attaching-flap 8 is preferably made of the same material as that of which 70 said band 6 is composed, and has one of its ends secured or fixed by means of a suitable rivet 9 to the curved exterior of 75 said band, at a point adjacent the free end of the latter, and the opposite end of said flap is provided with a suitable perforation 7, that is like or similar to the perforation in the handle-end of said band, Fig. 2, and the said perforated end of said flap is slipped into and through the inclined-slot 80 of the handle-jaw that is opposite that to which said band is pivoted, and is moved in its slot towards and into the adjacent perforation of the flap handle-jaw; thereby 85 pivotally attaching the perforated end of said flap to said flap handle-jaw.

The curved free end-portion 10 of the 90 said clamping-band 6 is arranged to overlap and slide upon the adjacent curved inner surface of said band, in closing around the piston 11, and the piston-ring or rings 12.

The operation.

The normal relative positions of the handles 1 and 2, as well as of the clamping-band 6, are those in which they are shown 95 in Fig. 1.

In placing piston-rings in the piston 11, the operator first places the expanded rings in the grooves of the piston, in the usual manner, and then places the clamping-band 6 around the said uncompressed rings, or a single ring if desired, and then closes the said band firmly upon the rings, by grasping the handle-portions of said handles 1 and 2, and brings the parts to the positions in which they are shown in solid lines in Fig. 1; whereupon the said piston-rings will be properly closed, and the piston carrying them may be quickly slipped into its cylinder.

105 I do not limit myself to the particular material which I have mentioned, as the 110

material may be changed, as may be the size and form of the members, without departing from the scope of my claims.

I claim:—

- 5 1. A tool for closing piston-rings, composed of crossed pivoted handles, a clamping-band having one of its ends pivotally-connected to one of said handles, and its opposite end arranged to slide in engagement with the inner surface of said band, in closing piston-rings, and a flap having one end fixed to the outer surface of said band at a point near the sliding end thereof, and having its opposite end pivotally-secured to the companion handle.
- 10 2. A tool for closing piston-rings, composed of crossed pivoted handles having inclined slots and perforations near their adjacent jaw-ends, a clamping-band having a perforation at one end that is pivotally-

engaged by the slotted and perforated portion of one of said handle jaw-ends, the opposite end-portion of said band being curved, and adapted to slide in contact with the inner surface of the band in closing piston-rings; and a flap having one of its ends secured to the outer surface of said band at a point near the said sliding-end thereof, and having a perforation at the end that is opposite its band-end, in which perforation said slotted and perforated portion of the companion handle jaw-end is pivotally located.

In testimony whereof, I have signed my name to this specification in presence of two subscribing witnesses.

CLARENCE E. SACRE.
